UNITED STATES PATENT OFFICE.

JACQUE L. MORGAN, OF KANSAS CITY, MISSOURI.

DESIGN FOR AN INSULATOR.

SPECIFICATION forming part of Design No. 30,564, dated April 18, 1899.

Application filed December 21, 1898. Serial No. 899,965. Term of patent 7 years.

To all whom it may concern:

Be it known that I, JACQUE L. MORGAN, a citizen of the United States, residing at Kansas City, in the county of Jackson and State 5 of Missouri, have invented and produced a new and original Design for Insulators, of which the following is a specification, reference being had therein to the accompanying drawings, forming part thereof.

Figure 1 is a front elevation, and Figs. 2 and 3 are the end elevations, of the insulator.

As shown in the drawings, the design consists of a tube B B', having a longitudinal rib

C extending along the side of the tube about 15 two-thirds of its length, the planes of the sides

of the rib being tangential to the side of the tube. A and A' are the perforations in the upper corners of the rib.

Having described my invention, what I claim as new, and desire to secure by Letters 20 Patent, is—

The design for an insulator, as herein shown and described.

In testimony whereof I affix my signature in presence of two witnesses.

JACQUE L. MORGAN.

Witnesses:

CLARENCE McELROY,
W. C. MOORE.
